E. C. CALKINS

REFRIGERATING RECEPTACLE

Filed Oct. 30, 1922

Inventor

Edward C. Calkins.

By Geo. H. Payne.

Attorney

UNITED STATES PATENT OFFICE.

EDWARD C. CALKINS, OF BROOKLYN, NEW YORK, ASSIGNOR TO I. C. REFRIGERATION COMPANY, A CORPORATION OF DELAWARE.

REFRIGERATING RECEPTACLE.

Application filed October 30, 1922. Serial No. 597,721.

To all whom it may concern:

Be it known that I, EDWARD C. CALKINS, a citizen of the United States, residing at Brooklyn, county of Kings, State of New York, have invented a new and useful Improvement in Refrigerating Receptacles, of which the following is a specification.

The present invention relates to a system and apparatus for refrigeration by heat exchange, and consists in the combinations and arrangements of elements hereinafter described and particularly set forth in the appended claims.

The invention has for its purpose to provide a refrigerating apparatus wherein the cooling is effected by convection currents of a fluid heat transfer medium in association with the material which it is desired to preserve; and wherein no operating mechanism of any character is employed.

A further purpose is the provision of an apparatus of this character adapted and suitable to the special requirements of small stores and like places where ice-cream and other perishable commodities are dispensed to a retail trade; and which may be kept in proper service at small cost without requiring any special knowledge or appreciable time of the attendant.

The invention is further characterized by compactness and simplicity, small cost of maintenance, and the employment of ice-brine as the refrigerant medium, which can be conveniently replenished and kept free of foreign matter and out of contact with the commodity preserved and for giving access to such commodity without hindrance to any other part or interference with the working of the system.

The invention is disclosed by way of illustration in the accompanying drawings, wherein:

Figure 1 is a top plan sectional view of the apparatus taken on the line 1—1 of Fig. 2, and

Fig. 2 is a longitudinal sectional view of the same taken on line 2—2, Fig. 1.

Referring to the construction in further detail, the apparatus consists of an outer receptacle or container preferably of rectangular shape and having double walls 3, providing a space for any suitable heat-insulating material 4, e. g., cork, asbestos, mineral wool or the like. The top of the receptacle is constructed to provide remov-

able closures 5 and 6 at the respective ends thereof, and an intermediate and relatively similar closure 7', and all of said closures are in like manner of double-walled construction to receive a filling of insulating material 4, as will the body portion of the receptacle. The two closures 5 and 6 may be hinged to the receptacle proper, or entirely removed as preferred, and give access to the two inner receptacles 7 and 8 constructed preferably of metal, which receive the several containers 9 as shown.

The two receptacles 7 and 8 are constructed preferably of metal and are mounted in the respective end portions of the outer receptacle, and in spaced relation thereto, by being supported on the two metallic bars 10 suitably secured to the bottom of the outer receptacle and extending the entire inner length thereof, as shown. Intermediate 75 the two receptacles 7 and 8 is a receptacle or container 11 constructed preferably of wire fabric, or other perforated body for holding the refrigerant medium, which in the present instance consists of ice-cooled brine. 80

The arrangement and relative proportions of the receptacles 7 and 8 and the refrigerant receptacle 11 are such that spaces 12 and 13 are provided to permit of convection currents to flow in a manner to 85 be further explained.

Between the side-wall portions of the inner and outer receptacles, and suitably secured therein, are arranged on opposite sides, two pairs of spacing members, in the 90 form of metallic strips 14 and 15 upwardly converging, as shown in Fig. 2, to provide suitable side spaces between the receptacles and partitioning the same in such manner that the convection currents will flow from 95 the respective lower ends of the outer receptacle upwardly and toward the refrigerant receptacle as indicated by the arrows. By this arrangement, the warmer currents of the refrigerant solution will constantly move towards colder central and upper parts of the refrigerator, and there will be cooled and continue to circulate entirely around the containers 9 in the receptacles 7 and 8. This will result in the maintenance of substantially uniform temperature throughout the course of the circulating refrigerant, with the result that the material in the containers will be maintained at substantially uniform temperature throughout. 105 110

The presence of the warmer brine currents passing through the endmost passages 12 will have no undesirable effect upon the material in the containers inasmuch as said 5 containers will be subjected to the influence of the coldest brine currents. In other words, the degree or range of temperature in all parts of the system is within such 10 limits that no appreciable deterioration of the commodity will occur.

It will therefore be seen from the foregoing that the apparatus may be maintained at maximum efficiency with small cost, and that the several containers 9, or the receptacles 15 7 or 8 easily replaced or removed without interference with any other part of the apparatus, and without interfering with the system of operation.

Draw-off faucet 16 communicates with 20 the lower portion of the receptacle, and a vent or similar fixture 17 communicates with the upper portion of the receptacle, as shown.

It is obvious that those skilled in the art 25 may vary the details of construction and arrangement of parts without departing from the spirit of my invention, and, therefore, I do not wish to be limited to such features except as may be required by the 30 claims.

What is claimed is:

1. A refrigerating apparatus comprising an outer receptacle, an inner receptacle, devices spacing the inner receptacle from said 35 outer receptacle and providing therewith a circuitous passageway for the refrigerant, and a container for the refrigerant located in the outer receptacle in communicating relation with said passageway, substantially 40 as set forth.

2. A refrigerating apparatus comprising an outer receptacle, an inner receptacle, devices between said receptacles providing therewith a circuitous passageway around 45 the inner receptacle for convection currents of a refrigerant solution, and a container for the refrigerant solution located in com-

municating relation with said passageway, substantially as set forth.

3. A refrigerating apparatus comprising 50 an outer receptacle, an inner receptacle, diagonally disposed spacing members between said receptacles at the sides thereof providing a circuitous passageway around the inner receptacle for convection currents of a refrigerant solution, and a container for the refrigerant solution located in the outer receptacle in communicating relation with said passageway, substantially as set 55 forth.

4. A refrigerating apparatus comprising 60 an outer receptacle, inner receptacles, diagonally disposed spacing members between said receptacles at the sides thereof providing circuitous passageways around the inner receptacles for directing opposed convection currents of a refrigerant solution, and a container for the refrigerant solution between said inner receptacles in communicating relation with said passageways, substantially as set forth.

5. A refrigerating apparatus comprising 65 an outer receptacle, opposed inner receptacles spaced from the bottom and end walls of the outer receptacle, opposed diagonal spacing members between said inner and outer receptacles at the sides thereof providing upwardly converging and circuitous passageways around the inner receptacles for directing convection currents of a refrigerant solution, and a perforated container for the refrigerant solution between said inner receptacles in communicating relation with said passageway, substantially 70 as set forth.

In testimony whereof, I have signed my name to this specification in the presence of two subscribing witnesses, this 27th day of October 1922.

EDWARD C. CALKINS.
